UNITED STATES PATENT OFFICE

114,639

DESIGN FOR A DOOR STOP

Edward W. Menger, San Antonio, Tex.

Application March 7, 1939, Serial No. 83,401

Term of patent 14 years

To all whom it may concern:

Be it known that I, Edward W. Menger, a citizen of the United States and a resident of San Antonio, in the county of Bexar and State of Texas, have invented the new, original, and ornamental Design for a Door Stop, of which the following is a specification.

Reference is had to the accompanying drawing forming part thereof.

I claim:

The ornamental design for a door stop, as shown.

EDWARD W. MENGER.
